INKER MECHANISM

John Kunz, Pittsburgh, Pa., assignor to Miller
Printing Machinery Co., Pittsburgh, Pa., a cor-
poration of Pennsylvania

Original application August 3, 1940, Serial No.
350,705. Divided and this application October
17, 1941, Serial No. 415,402

12 Claims. (Cl. 101—358)

This invention relates to inker mechanism for printing presses and the like. It relates more particularly to control of the form inking rollers and to the raising of such rollers to a position out of the path of the form, as is desirable when the mechanism is stopped for an appreciable period. The invention relates still more particularly to mechanism for raising the form inking rollers and operating means therefor. This application is a division of my copending application Serial No. 350,705, filed August 3, 1940.

The invention, although not specifically so limited in all of its aspects, will be described as embodied in an inker for a flat bed and cylinder type printing press. In presses of this type the bed is ordinarily arranged horizontally and is in planar form and oscillates back and forth beneath the printing cylinder. The form is mounted on top of the bed. The form is inked by form inking rollers, commonly called simply "form rollers," which are mounted above the path of the form and which when in operative position roll upon the surface of the form to deliver ink thereto.

Form rollers are generally soft surfaced and made of what is known in the art as "composition" so as most effectively to ink the form. When the press is stopped for an appreciable period the composition form rollers are desirably raised out of the path of the form so that there will be no possibility that they will lie in contact with the form while the parts are stationary. Various provisions for raising the form rollers out of the path of the form have heretofore been made. Such provisions have in the main entailed the use of complicated and relatively costly mechanism which further increases the complexity and cost of the already complex and expensive inker. Moreover, in some cases the means for thus raising the form rollers have not effectively performed the desired function.

I provide means for effectively raising the form rollers of an inker out of the path of the form, which means are extremely simple and inexpensive in structure, easy and foolproof in operation and reliable in use. I prefer, instead of bodily lifting the form rollers while maintaining them in fixed orientation as has heretofore been customary, to tilt the form rollers, thus avoiding disturbing the bearing at one end of each form roller and greatly reducing the complexity and cost of the means for moving the form rollers to a position out of the path of the form. I provide simple and effective means for raising

5 at least one end of each form roller including roller raising means at the inside of the frame, operating means therefor at the outside of the frame and connections therebetween whereby the raising of the form rollers may be easily and effectively accomplished.

Other details, objects and advantages of the invention will become apparent as the following description of a present preferred embodiment 10 thereof proceeds.

In the accompanying drawing I have shown a present preferred embodiment of the invention, in which

15 Figure 1 is a fragmentary plan view of a portion of an inker showing the form rollers and the means for raising the same to a position out of the path of the form;

20 Figure 2 is a fragmentary elevational view of the form rollers and raising means shown in Figure 1, the form rollers being indicated in raised position in chain lines; and

25 Figure 3 is a fragmentary vertical transverse cross-sectional view showing the means for raising the form rollers.

30 Referring now more particularly to the drawing, there is provided a frame designated generally by reference numeral 2 relative to which the press bed carrying the form oscillates. Since the bed and form constitute no part of the present invention they are not shown in the drawing. The form is mounted upon the bed and the bed oscillates horizontally. During such oscillation the surface of the form is at the elevation indicated by the chain line A in Figure 2.

35 There are provided three form rollers 4, 5 and 6 for delivering ink to the form. Ink is delivered to and distributed upon the form rollers 4, 5 and 6 by means well known in the art, and since such means constitute no part of the present invention they are not shown. The roller 4 is mounted upon a shaft 253, the roller 5 is mounted upon a shaft 254 and the roller 6 is mounted upon a shaft 255. The right-hand ends 40 of the shafts 253, 254 and 255 viewing Figure 1 are mounted in bearings 256, 257 and 258, respectively, while the left-hand ends of such shafts are mounted in bearings 259, 260 and 261, respectively. The bearings 256 and 259 are alike, the bearings 257 and 260 are alike and the bearings 258 and 261 are alike. The bearings 259, 260 and 261 are clearly shown in Figure 2. Each 45 thereof comprises a downwardly extending stem 262 extending within a socket 263 in a bearing block 264 carried by the frame 2. A set screw

265 provided with an adjusting nut 266 enters each of the sockets 263 axially at its bottom, the stems 262 normally resting on the ends of the set screws as shown in Figure 2. Thus the operative positions of the form rollers 4, 5 and 6 may readily be adjusted.

The bearing 259 comprises a half yoke 267 carried by its stem 262, a spring pressed latch 268 cooperating with the half yoke 267 to hold one end of the shaft 253 therein as shown in Figure 2. The bearing 260 comprises a yoke 269 carried by its stem 262, the yoke 269 facing upwardly as shown in Figure 2 and containing one end of the shaft 254. The bearing 261 comprises a yoke 270 carried by its stem 262, the yoke 270 facing at an angle of about 45° upwardly and to the left as shown in Figure 2 and containing one end of the shaft 255.

The frame 2 carries a pin 271 to which is pivoted a link or arm 272. Pivoted to the link 272 at 273 is an elevating member 274 which normally lies below and out of contact with the ends of the shafts 253, 254 and 255 immediately adjacent the bearings 259, 260 and 261. The opposite end of the elevating member 274 is pivoted at 275 to an arm 276 fixed to a shaft 277. Also fixed to the shaft 277 is an operating handle 278. Upon turning of the operating handle 278 the elevating member 274 is swung generally upwardly and somewhat to the left viewing Figure 2 upon the arm 276 and the link or arm 272 and upon such movement it engages the shafts 253, 254 and 255 immediately adjacent the bearings 259, 260 and 261 and thereby raises one end of each of the three form roller shafts, also raising, of course, one end of each of the three form rollers. The elevating member 274 and its operating mechanism are so designed and proportioned that such member will raise one end of each of the three form rollers sufficiently that all of the form rollers will be moved to a position in which they will be entirely out of engagement with the form, even if the form be positioned immediately below the form rollers.

Since the end of the shaft 253 is locked within the half yoke 267 by the latch 268, upward movement of such end of the shaft 253 is necessarily accompanied by upward movement of the bearing 259, which is permitted by reason of the fact that the stem 262 thereof is loosely and slidably received within the corresponding socket 263. Since the yoke 269 opens directly upwardly the end of the shaft 254 will simply be raised out of such yoke by the elevating member and the yoke will remain in place as shown in Figure 2. The end of the shaft 255 positioned by the yoke 270 will either slide up at an angle within the yoke while the yoke remains stationary or carry the yoke up with it upon being raised by the elevating member 274, depending on whether the friction between the shaft end and the yoke is greater or less than the friction between the stem 262 of the bearing 261 and its socket 263. However this may be, each of the three form rollers may be tilted by the elevating member 274 as above described to position it at a point offset from the path of the form. The elevating member 274 is used for thus tilting the form rollers only when the means for delivering ink to the form rollers are raised out of contact therewith, for which provision is made in the inker. When the inker is not being used the form rollers should be raised. This should be done not only when use of the press is discontinued at the end of the day but also, for ex-

ample, in stopping for lunch or when for some other reason it is necessary to stop the press for an appreciable period of time.

While I have shown and described a present preferred embodiment of the invention it is to be distinctly understood that the invention is not limited thereto but may be otherwise variously embodied within the scope of the following claims.

10 I claim:

1. In an inker, a plurality of form inking rollers and common means including a rapidly shiftable operating member for tilting said rollers simultaneously to a position out of the path of the form.

15 2. In an inker, a plurality of form inking rollers and means including a rapidly shiftable operating member for simultaneously lifting one end only of each of said rollers sufficiently to move said rollers to positions entirely out of the path of the form.

20 3. In an inker, a form inking roller, bearings for said roller adjacent its ends and means separate from said bearings engaging said roller adjacent one of said bearings to raise an end of the roller whereby to tilt the roller to a position out of the path of the form.

25 4. In an inker, a form inking roller, bearings for said roller adjacent its ends and means for raising one end only of the roller relatively to the bearing adjacent that end whereby to tilt the roller to a position out of the path of the form.

30 5. In an inker, a form inking roller, bearings for said roller adjacent its ends and means including a manually operable handle for raising one end only of the roller together with the bearing adjacent that end whereby to tilt the roller to a position out of the path of the form.

35 6. In an inker, a frame, a form inking roller carried by the frame and means including an operating member carried by the frame at the outside thereof for raising one end only of the form roller to tilt it to a position out of the path of the form.

40 7. In an inker, a frame, a form inking roller carried by the frame and means including an operating member at the outside of the frame and a member at the inside of the frame operable upon operation of said operating member to raise one end only of the form roller whereby to tilt it to a position out of the path of the form.

45 8. In an inker, a frame, a form inking roller carried by the frame, a pair of pivots carried by the frame, an arm mounted on each pivot and means carried by said arms and adapted to rise upon angular movement of said arms about said pivots to raise one end only of the form roller whereby to tilt it to a position out of the path of the form.

50 9. In an inker, a frame, a form inking roller carried by the frame, pivot means carried by the frame, roller raising means connected with said pivot means and manually operable means for moving said roller raising means relatively to said pivot means to raise the form roller to a position out of the path of the form.

55 10. In an inker, a frame, a form inking roller carried by the frame, roller raising means at the inside of the frame, a manually operable operating member at the outside of the frame and connections between said operating member and said roller raising means whereby the former operates the latter to raise the form roller to a position out of the path of the form.

11. In an inker, a frame, a form inking roller carried by the frame, a pair of pivots carried by the frame, roller raising means at the inside of the frame and connected with said pivots and manually operable means at the outside of the frame to raise the roller raising means relatively to said pivots whereby to raise the form roller to a position out of the path of the form.

12. In an inker, a frame, a form inking roller carried by the frame, a pair of pivots carried by the frame, an arm mounted on each pivot, roller

raising means carried by said arms at the inside of the frame and adapted to rise upon angular movement of said arms about said pivots, a manually operable operating member at the outside of the frame and connections between said operating member and said arms whereby upon operation of said operating member said roller raising means is caused to rise whereby to raise the form roller to a position out of the path of the form.

JOHN KUNZ.
